(57) **CLAIM**

The ornamental design for a therapeutic pressure application device, as shown and described.

DESCRIPTION

FIG. 1 is a top perspective view of a therapeutic pressure application device, showing my new design, broken lines depicting environment that forms no part of the claimed design;

FIG. 2 is a top perspective view thereof, environment depicted in FIGS. 1, 3-6, and 9 being omitted;

FIG. 3 is a front elevational view thereof, broken lines depicting environment that forms no part of the claimed design;

FIG. 4 is a rear elevational view thereof, broken lines depicting environment that forms no part of the claimed design;

FIG. 5 is a left side elevational view thereof, broken lines depicting environment that forms no part of the claimed design;

FIG. 6 is a right side elevational view thereof, broken lines depicting environment that forms no part of the claimed design;

FIG. 7 is a top plan view thereof, environment depicted in FIGS. 1, 3-6, and 9 being omitted;

FIG. 8 is a bottom plan view thereof, environment depicted in FIGS. 1, 3-6, and 9 being omitted, broken lines depicting a portion of the therapeutic pressure application device that forms no part of the claimed design;

FIG. 9 is a front elevational view thereof, broken line circle indicating a portion detailed in FIG. 10, other broken lines depicting environment that forms no part of the claimed design; and,

FIG. 10 is an enlarged front elevational view for the portion indicated in FIG. 9.

1 Claim, 5 Drawing Sheets
